JOSEPH SCHWERTNER, OF NEW YORK, N. Y., ASSIGNEE TO HEERWAGEN COMPANY,
A CORPORATION OF NEW YORK.

BLEED-HOLE-REGULATING DEVICE.

1,107,851.

Specification of Letters Patent. Patented Aug. 18, 1914.

Application filed April 1, 1913. Serial No. 758,110.

To all whom it may concern:

Be it known that I, JOSEPH SCHWERTNER, a citizen of the United States, and a resident of New York, county of New York, and 5 State of New York, have invented certain new and useful Improvements in Bleed-Hole-Regulating Devices, of which the following is a specification.

My invention relates to improvements in 10 pneumatic apparatus, and more especially to a device such as shown in reissued Letters Patent of the United States, No. 13384, March 12, 1912.

In self playing pianos it is customary to 15 provide a pneumatic device for operating each action unit and a tracker board and sheet with apertures corresponding to the various notes for controlling the operation thereof. Between the tracker and operating 20 pneumatics, however, it is usual to place one or more controlling pneumatics for controlling the action of the operating pneumatics responsive to the operation and particular design of the note sheet. In most instances these intermediate pneumatics are 25 controlled and operated by means of suction or a partial vacuum produced by suitable bellows. In organs the action is similar except that it is usual to operate the various 30 devices by wind pressure, that is, by blowing action rather than by suction. In both instances, however, it is usual to provide pneumatic actions with an operating membrane and with a bleed hole leading to one side of 35 the membrane in order to allow of an equalization of pressure on that side of the membrane when it is desired to close a valve. In 40 said reissued Letters Patent No. 13384, a device is described by which such bleed holes will be automatically cleaned and by which 45 the effective cross section of the bleed hole will be varied to render the actions more sensitive. The apparatus herein similarly acts to clean and vary the cross section of 50 the bleed hole, but in the arrangement of said reissued Letters Patent when the membrane is operated the effective cross section of the bleed hole remains increased until the 55 action is returned to its normal position, while in the present invention I provide an arrangement which acts to substantially close the bleed hole at both of the extreme positions of the operating membrane of the action, or when the action is at both of its rest positions.

Further features and advantages will more

clearly appear from the detailed description given below taken in connection with the accompanying sheet of drawings, in which—

Figure 1 is a section through a pneumatic action and power pneumatic for use in an automatic piano player; Fig. 2 is a similar section through the bleed hole and parts adjacent thereto, showing the operating membrane in its lower rest position; Fig. 3 is a 60 similar view showing the membrane in mid-position; Fig. 4 is a similar view showing the membrane in its upper rest position; Fig. 5 is a detail section illustrating a modification of the bleed hole regulating device; 65 Fig. 6 is a section through the spindle of Fig. 5; Fig. 7 is a view similar to Fig. 5, but illustrating a further modification, and Fig. 8 is a section through the spindle shown in Fig. 7. 70

Referring to Figs. 1 to 4, 1 represents a power pneumatic adapted to be exhausted through the passage 2. 3 is a port leading from the passage 2 to the outside atmosphere. 4 represents a chamber in which is 80 located the membrane 5 of the pneumatic action. The chamber 4 is connected to the passage 2 by way of a port 6 and a valve is adapted to close either the port 3 or port 6, according as the valve is in its upper or 85 lower position. The valve 7 carries rigidly on its bottom a stud 8 passing through the port 6 and cut away as at 9, to allow the air to be exhausted from the passage 2 and pneumatic 1 into the chamber 4. The mem- 90 brane 5 has secured thereto a washer 10 through which passes a metal spindle 11 firmly secured to the washer. The lower end of the stud 8 is cut away as at 12 to freely accommodate the upper end of the 95 spindle. 13 represents a wind trunk through which the chamber 4 above the membrane 5 is adapted to be exhausted by means of a passage 14. A port 15 leads from the space beneath the membrane 5 toward the wind 100 trunk 13, the lower end of the port being covered by a metal plate 16 except at the center where a bleed hole 17 extends through the plate 16 through which the air may be exhausted from the under side of the mem- 105 brane 5 when the membrane 5 and valve 7 are returned to their normal position.

The parts so far described operate in a manner that will be readily understood by those skilled in the art. Air being admitted 110 through the passage 18 (Fig. 1) under atmospheric pressure and the chamber 4 being

under constant suction by its connection with the wind trunk 13, the membrane 5 will be forced upwardly carrying with it spindle 11 and washer 10. The washer 10 will impinge upon the bottom of the stud 8 and thereby raise the valve 7 so as to close the port 3 and open the port 6, whereupon the pneumatic 1 is exhausted through the passage 2, port 6, etc., to cause one of the piano strings to be struck in a well known manner. The spindle 11 is cut away at 19 where the spindle operates in the bleed hole 17, and when the membrane is in its extreme lower position or lower position of rest, as shown in Fig. 2, the bleed hole is substantially closed by that part of the spindle above the cut away portion. When the pneumatic action is in its upper extreme position of rest, as shown in Fig. 4, the bleed hole is substantially closed by that portion of the spindle below the cut away portion, and when the membrane is in mid position, as shown in Fig. 3, the bleed hole is materially opened or its effective cross section is materially increased by means of the cut away portions 19, which extend for a greater distance than the thickness of the plate 16.

It will be understood that while the bleed hole is substantially closed when the action is either in its upper or lower position of rest, nevertheless, there is sufficient leakage about the uncut-away part of the spindle to give the membrane a downward movement when the parts are in the position shown in Fig. 4, and the atmospheric pressure is shut off from the passage 18. A slight downward movement of the membrane, due to this leakage, soon brings the spindle down where it greatly opens the bleed hole, as shown in Fig. 3, whereupon the air is quickly exhausted from beneath the membrane 5 through the bleed hole 17, and the parts quickly returned to their normal position of rest, and during the latter part of this movement the bleed hole is substantially closed by the uncut-away part of the spindle above the cut-away portion, as shown in Fig. 2. It will thus be seen that there is practically no loss of air through the bleed hole when the action is in either of its positions of rest, but the bleed hole is only materially opened at the time when it is desired to exhaust a material volume of air therethrough, thereby making a great saving in power, and at the same time getting quick action of the parts and making the device very sensitive.

Figs. 5, 6, 7 and 8 show two more of the various methods by which the spindle 11 may be cut away where it operates in the bleed hole.

The bleed hole will be automatically cleaned by the faces 20 pushing dust and dirt therethrough.

Many modifications and changes may be made in the arrangements shown without departing from the spirit and scope of my invention and I, therefore, do not desire to be limited to the details shown and described except as clearly specified in the appended claims.

Having fully and clearly described my improvements, what I claim as new and desire to secure by Letters Patent of the United States, is:

1. In a device of the class described, a pneumatically operating membrane or diaphragm, a bleed hole therefor, and means to substantially close the bleed hole when the membrane is at either of its extreme positions and to materially open the bleed hole when the membrane is intermediate its extreme positions.

2. In a device of the class described, a pneumatic action having a bleed hole, and means for increasing the effective cross-section of the bleed hole when the action is operated pneumatically, and substantially closing the bleed hole when the action is at rest in both of its rest positions.

3. In a device of the class described, a pneumatic action having a bleed hole and a spindle operating in the bleed hole and controlled by the pneumatic action, said spindle being cut away at the part operating in the bleed hole to increase the effective cross section of the bleed hole when the action operates, the spindle above and below the cut-away portion acting to substantially close the bleed hole when the action is at rest in both of its rest positions.

4. In a device of the class described, a pneumatically operating membrane, a bleed hole through which the air on one side of said membrane may be exhausted, and a spindle connected to said membrane and operated thereby and within the bleed hole, said spindle being cut away at the part operating in the bleed hole to increase the effective cross section of the bleed hole when the action operates, the spindle above and below the cut away portion acting to substantially close the bleed hole when the action is at rest in both of its rest positions.

In testimony whereof, I have signed my name to this specification, in the presence of two subscribing witnesses.

JOSEPH SCHWERTNER.
